UNITED STATES PATENT OFFICE

EDWIN O. KLEMM AND NORMAN L. POLLARD, OF SAGINAW, MICHIGAN

DESIGN FOR A COMBINED LAMP, CHAIR, AND CABINET FURNITURE UNIT

Application filed November 20, 1930. Serial No. 37,738. Term of patent 14 years.

To all whom it may concern:

Be it known that we, EDWIN O. KLEMM and NORMAN L. POLLARD, citizens of the United States, residing at Saginaw, in the county of Saginaw and State of Michigan, have invented a new, original, and ornamental Design for Combined Lamp, Chair, and Cabinet Furniture Unit, of which the following is a specification, reference being had to the accompanying drawing, forming a part thereof, in which—

The figure is a perspective view of a combined lamp, chair, and cabinet furniture unit showing our new design.

We claim:—

The ornamental design for a combined lamp, chair, and cabinet furniture unit, substantially as shown.

EDWIN O. KLEMM.
NORMAN L. POLLARD.
